UNITED STATES PATENT OFFICE

EARL C. BOOTH, OF INDIANAPOLIS, INDIANA, ASSIGNOR TO NOBLITT-SPARKS INDUSTRIES, INC., OF COLUMBUS, INDIANA, A CORPORATION OF INDIANA

DESIGN FOR A HEATER CASING

Application filed March 26, 1932. Serial No. 43,299. Term of patent 7 years.

To all whom it may concern:

Be it known that I, EARL C. BOOTH, a citizen of the United States, residing at Indianapolis, in the county of Marion and State of Indiana, have invented a new, original, and ornamental Design for a Heater Casing, of which the following is a specification, reference being had to the accompanying drawing, forming part thereof.

Figs. 1 and 2 are perspective views illus-

trating respectively the front and rear faces of the casing of my new design.

I claim:

The ornamental design for a heater casing, as shown.

In witness whereof, I have hereunto set my hand at Columbus, Indiana, this 23d day of March, A. D. one thousand nine hundred and thirty-two.

EARL C. BOOTH.
